UNITED STATES PATENT OFFICE

154,352

DESIGN FOR A TABLE LAMP

Siegbert Wetterhahn, New York, N. Y.

Application March 26, 1947, Serial No. 137,896

Term of patent 7 years

(Cl. D48—20)

To all whom it may concern:

Be it known that I, Siegbert Wetterhahn, a citizen of the United States of America, residing in the city, county, and State of New York, have invented a new, original, and ornamental Design for a Table Lamp, of which the following is a specification, reference being had to the accompanying drawing, forming a part thereof.

Fig. 1 is a perspective view of a table lamp, showing my new design, the box covers being shown in partly opened positions;

Fig. 2 is a sectional view thereof, taken on the line 2—2 of Fig. 1.

I claim:

The ornamental design for a table lamp, as shown.

SIEGBERT WETTERHAHN.
